UNITED STATES PATENT OFFICE

2,406,388

TURBOSUPERCHARGER

Anthony J. Larreeq, Indianapolis, Ind., assignor
to General Electric Company, a corporation of
New York

Application June 10, 1941, Serial No. 397,378

4 Claims. (Cl. 184—6)

1

The present invention relates to turbosuperchargers comprising a centrifugal compressor and an exhaust gas operated turbine for driving the compressor such as are used for supercharging internal combustion engines and like consumers of air under pressure.

The object of my invention is to provide an improved construction and arrangement of turbosupercharger whereby good efficiency and economy are attained.

For a consideration of what I believe to be novel and my invention, attention is directed to the following description and the claims appended thereto in connection with the accompanying drawings.

The drawing Fig. 1 illustrates a sectional view of a turbosupercharger embodying my invention; Fig. 2 is a section along line 2—2 of Fig. 1; and Fig. 3 is a sectional view along line 3—3 in Fig. 2.

The turbosupercharger, as shown in the drawings, comprises a gas turbine 10, a centrifugal type compressor 11, and a speed-increasing gearing 12 for driving the compressor from the gas turbine and for supporting the turbine on the compressor. Turbosuperchargers, especially when used on aircraft, are operated at high speeds of the order of 20,000 R. P. M. and above. The provision of a speed-increasing gearing for driving the compressor from the turbine permits the operation of the turbine at a speed lower than that of the compressor and results in a compact design with the outer dimensions of the compressor substantially equal to the outer dimensions of the turbine. My invention particularly relates to an improved arrangement for lubrication of such gearing.

The gas turbine comprises three essential elements, a bucket wheel 13, a nozzle box 14 for conducting gases to the wheel, and a protecting and cooling device 15 for cooling and protecting the bucket wheel 13. The bucket wheel has a disk 16 and a row of circumferentially spaced buckets 17 secured to the rim of the disk 16. The bucket wheel is secured to a hollow flanged shaft 18 forming a bore 19 by means of a plurality of bolts 20.

The nozzle box has an essentially ring-shaped casing 21 with a flanged inlet 22 for connection to a source of operating medium such as the exhaust manifold of an internal combustion engine. Operating gas is discharged from the nozzle box to the turbine wheel by means of a plurality of nozzles formed by circumferentially spaced partitions 23 secured to and supported on the casing 21.

2

In order to reduce the radiation of heat from the nozzle box, a jacket is provided which substantially incloses the wall of the nozzle box. The jacket has flanged walls 24, 25 spaced from the casing 21 and supported thereon by connecting and supporting members 26. An inner portion of the wall 24 forms a plurality of openings 27 for conducting cooling medium to the space formed between the casing 21 and the walls 24, 25 and 26 of the jacket. The cooling medium is discharged from said space through a plurality of openings 28. The lower portion of the nozzle box forms a waste conduit 29 for discharging some of the gases conducted to the box; that is, for bypassing some of the gases with regard to the turbine wheel. The discharge through the waste conduit 29 may be regulated by a waste gate 30 indicated in Fig. 1 in closed position. The openings 28 for discharging cooling medium from the aforementioned jacket are arranged in the position of the casing 21 which forms the waste conduit 29, and with regard to the valve 30, the openings 28 are arranged at a point beyond the valve 30 as regards the direction of flow of gas through the waste conduit.

The jacket wall 24 is provided with a plurality of lugs 31 for supporting the nozzle box on the gearing 12.

In order to cool the downstream side of the turbine wheel, a suitable cooling cap may be used, as shown in Fig. 1. The details of this cooling cap are not material to an understanding of the present invention; and other suitable types may be used, such as those disclosed in U. S. Patent 2,364,037, filed in the name of Chester W. Smith and assigned to the same assignee as the present application.

The compressor 11 comprises a casing having two halves 61 and 62 suitably flanged together and forming an impeller chamber 63 and a discharge scroll 64 surrounding the impeller chamber 63. A central portion of the casing half 61 forms an inlet conduit 65 for receiving air or like medium to be compressed. An impeller having a disk 66 and a plurality of circumferentially spaced blades 67 is located in the impeller chamber and secured to a shaft 68 by means including a nut 69. A plurality of circumferentially spaced auxiliary impeller blades 70 are secured to and integrally formed with the nut 69. A set of fluid directing vanes 71 is arranged ahead of the auxiliary impeller blades 69 and supported on and secured to the inlet conduit 65. The inner edges of the blades 71 are secured to a curved dish-shaped cup 72 adjacent the nut 69. Another set

of circumferentially spaced fluid directing vanes or nozzle partitions 73 is arranged between the auxiliary blades 69 and the main blades 66. A wire mesh screen 74 held between two rings 75 is secured to the inlet conduit 65 to reduce access of solid matter into the interior of the compressor.

During operation the set of vanes or partitions 71 direct fluid to be compressed towards the auxiliary blades 16. The latter impel such fluid in axial direction towards the vanes 73 which, in turn, direct the fluid towards the inlet portions of the main impeller blades 67. The fluid is impelled by the blades 67 mainly by centrifugal action and forced radially outward into the scroll 64.

A diffuser 79 is provided for converting part of the velocity energy of the medium impelled by the impeller 63 into pressure energy. The diffuser 79 is located in a central portion of the scroll 64 and comprises a plurality of vanes 80 having opposite edges secured to rings 81 and 82 centered on the two casing halves 61 and 62 respectively. The rings or walls 81 and 82 are rigidly secured to the casing halves 61 and 62 by means of a plurality of circumferentially spaced bolts 83 and 84 respectively. An outer portion of the compressor casing forms a flanged opening 85 for discharging compressed medium to a consumer such as an internal combustion engine.

The gearing 12 for driving the compressor from the turbine and for supporting the latter on the compressor comprises a casing 90 having three outer arms or brackets 91 with axial bores 92 for receiving the bolts 84. These bolts project through openings in the aforementioned brackets 91 of the nozzle box and are rigidly secured to the brackets 91 and the brackets 91 by means of nuts 93 thus forming a rigid support for the gearing and the nozzle box on the compressor casing.

The ends of the casing 90 are closed by end covers 94 and 95 rabbeted to the casing 90. The turbine shaft 18 and the compressor shaft 68 project through openings in the end covers 95 and 94 respectively, and adjacent end portions of the shafts telescope each other. More specifically a bearing sleeve 96 is secured in the bore 19 of the turbine shaft 18 and supports the right-hand end portion of the compressor shaft 68. The left-hand end of the hollow turbine shaft 18 is supported on a journal bearing 97 secured to an inner wall or partition 98 of the casing 90. A portion of the turbine shaft 18 near the bucket wheel 13 is supported by another journal bearing 99 secured to an inner cylindrical projection of the end cover 95. Similarly, a portion of the compressor shaft near the impeller is supported on a journal bearing 100 secured to the end cover 94.

The turbine shaft 18 is provided with a pinion or gear 101 located between the bearings 97 and 99 and the compressor shaft 68 is provided with a gear 102 arranged between the bearings 97 and 100. Torque is transmitted from the gear 101 on the turbine shaft to the gear 102 on the compressor shaft by means of an intermediary shaft 103 with two axially spaced gears 104 and 105 secured thereto and meshing with the gears 101 and 102 respectively.

The outer ends of the intermediary shaft 103 are supported by journal bearings 106 and 107 respectively, secured to the inner wall of the gear housing.

The gearing 12 also includes means for lubricating the various bearings and gears and means to reduce leakage of lubricant from the casing 90 along the shafts 18 and 68. The means to reduce leakage along the shaft 68 comprise labyrinth type packings 115 and means including said packing to form a leak-off chamber 116 between the packing 115 and the adjacent bearing 100 for receiving lubricant discharged from the left-hand end of the bearing 100. Another labyrinth type packing 117 is provided to reduce leakage from the casing 90 along the shaft 18. The packing 117 and the adjacent bearing 99 form another leak-off chamber 118 for receiving lubricant discharged from the right-hand end of the bearing 99.

The space formed by the lower portion of the casing 90 between the bearings 100 and 99 forms another chamber 119 for receiving lubricant from these bearings and from other elements of the gearing. In order to assure thorough lubrication of the various elements of the gearing, a pump 120 (Fig. 2) is provided for conducting oil or like lubricant to the various elements requiring lubricant during operation and three other pumps 121, 122 and 123 are provided for removing lubricant from the chambers 116, 118 and 119.

The pump 121 has an inlet 124 connected by passages 125, 126 and 127 formed in internal and external ribs of the casing 90 (Fig. 2) to both leak-off chambers 116 and 118. It should be noted that the passage 126 is in front of the plane of the section represented by Fig. 1, whereas the other horizontal passages 130 and 132 are behind that plane. From a comparison of Figs. 1 and 2 it will be understood that the mid-point of the horizontal passage 126 is connected to the pump inlet chamber 124 by the single vertical passage 125.

The pump 122 has an inlet 129 connected by passages 130, 130 formed in an internal rib of the casing 90 to the left-hand part (Fig. 1) of the main chamber 119. The pump 123 has an inlet 131 connected by passages 132, 132 to the right-hand part (when viewed in Fig. 1) of the main chamber 119. The provision of two pumps 122 and 123 for removing oil from opposite ends of the main chamber 119 is desirable in order to assure thorough scavenging of this chamber in the various positions the gearing may assume when used on an aircraft.

The pump 120 for supplying lubricant to the various bearings and gears has an inlet 133 connected to a supply conduit 134 for receiving lubricant from a source not shown. The pump 120 has an outlet 135 connected by suitable channels (not shown) to the various elements to be lubricated. The detail arrangement of these channels is not indicated in the drawings as it does not form a part of the present invention.

The lubricant removed from the chambers 116, 118 and 119 by the scavenging pumps 121, 122 and 123 is discharged from said pumps into a drain conduit 140. The conduit 140 is connected to a discharge passage 141 communicating directly with the outlets 142 and 143 of the pumps 122 and 123 respectively. The discharge passage 141 is connected by a passage 144 formed in the casing 90 to the outlet 145 of the pump 121.

The four pumps 120, 121, 122 and 123 are of conventional gear type design and have driven elements or rotors suitably connected to a common drive shaft 146 which latter has a gear 147 meshing with a gear 148 secured to, in the present example integrally formed with, the shaft 103.

and located between the gears 104 and 105 on this shaft. The gears 147 and 148 are spiral gears with their axis of rotation arranged at right angles to each other.

Fig. 3 shows the details of the scavenger pump at the extreme right end of the shaft 146 in Fig. 2. This pump consists of gear 121', which may be pressed or keyed onto an extension 146' of the shaft 146, meshing with a second gear 124' supported on suitable bearings (not shown) in the pump housing. As indicated above, oil from passage 125 enters the pump inlet chamber 124, is carried by the gear teeth to the discharge chamber 145, from whence it goes through passage 144 to the oil-out passage 141. The gears 121', 124' are separated from the corresponding elements of oil supply pump 120 by a plate 121', which is arranged to fit closely the perimeter of the recess in the pump housing occupied by the pump gear elements, the plate 121' having suitable openings through which pass the pump gear shafts.

The above-described oil pump arrangement is representative of the arrangement of the other gear pumps 120, 122, 123.

As stated above the end covers 94 and 95 are rabbeted to the casing 90. They are rigidly secured to the casing by a plurality of circumferentially spaced studs 149 threaded into the end cover 95 and projecting through bores 150 formed in ribs 151 of the casing 90. The ribs 151 extend from the inner face of the end cover 95 to the adjacent inner face of the end cover 94. They act to reinforce the casing and what is more important they reduce leakage of lubricant along the studs through the openings in the end cover 94. The end cover 94 is securely fastened to the studs 149 by nuts 152.

The outer lower portion of the gearing casing 90 forms a curved channel 155 which may be connected to a conduit or scoop 156 for receiving air under pressure from the slip stream. Such air or cooling medium is conducted through the channel 155 and discharged into the space 157 formed between adjacent portions of the gearing casing, the bucket wheel and the nozzle box. Part of the cooling medium is forced from the space 157 through the openings 27 into the space formed between the cooling jacket 24, 25 and 26 and the nozzle box casing 21.

What I claim as new and desire to secure by Letters Patent of the United States:

1. Gearing comprising a casing, two aligned shafts having end portions overhanging from the casing and other end portions telescoping each other and supported on a central portion of the

casing, means for transmitting torque between the two shafts, the central portion of the casing forming an oil chamber and end portions of the casing forming leak-off chambers, means for lubricating the gearing comprising a pump driven from one of the shafts for forcing lubricant into the gearing and separate scavenging pumps connected to the leak-off chambers and the intermediate chamber for removing lubricant therefrom.

2. A gearing for aircraft turbosuperchargers comprising a casing with open end portions, covers having central openings secured to the end portions, a driving shaft and a driven shaft in alignment and supported on the covers, means including an intermediate gear shaft supported on the casing for connecting the driving and driven shafts, means including a pump for supplying lubricant to the elements of the gearing, means for removing lubricant from the gearing comprising a main chamber formed by a central portion of the casing, leak-off chambers formed by the end covers, scavenging pumping means for removing lubricant from both ends of the main chamber and other scavenging pumping means connected to both leak-off chambers for removing lubricant therefrom, and means for driving all of the pumping means from one of said shafts.

3. A system of lubrication for a gearing having a housing, shaft and gear means enclosed therein, leak-off chambers formed at the ends of the housing and a main oil chamber formed by a central portion of the housing, said system comprising separate scavenging pump means for removing oil from the leak-off chambers and the housing respectively, pumping means for supplying lubricant to the gearing, said pumping means having casings formed at least partly by said housing, and means for driving all of said pumping means from one of the shaft means.

4. A system for lubricating a gearing having a housing, shaft and gear means enclosed therein and detachable end covers for the housing forming supports for the shaft means and leak-off chambers for receiving lubricant leaking along the shaft means, a main chamber for lubricant being formed by the housing, a pump for supplying lubricant to the shaft and gear means, a scavenging pump for removing lubricant from the main chamber, scavenging pump means for removing lubricant from the leak-off chambers, and means including a gear shaft adapted to be driven from one of the shaft means for driving all of said pumps.

ANTHONY J. LARRECQ.
